UNITED STATES PATENT OFFICE

117,601

DESIGN FOR A TIRE CASING

Francis J. Snyder, West Haven, Conn., assignor
to The Armstrong Rubber Company, Incorporated, West Haven, Conn., a corporation of
New Jersey

Application January 21, 1939, Serial No. 82,507

Term of patent 7 years

To all whom it may concern:

Be it known that I, Francis J. Snyder, a citizen of the United States, residing at West Haven, in the county of New Haven and State of Connecticut, have invented a new, original, and ornamental Design for a Tire Casing, of which the following is a specification, reference being had to the accompanying drawings, forming part thereof.

Fig. 1 is a perspective view partly in dotted lines of a tire casing showing my new design;

Fig. 2 is a transverse sectional view thereof;
and

Fig. 3 is a broken developed plan view thereof.

I claim:

The ornamental design for a tire casing, substantially as shown.

FRANCIS J. SNYDER.
